[57] CLAIM

The ornamental design for hand luggage, as shown and described.

DESCRIPTION

FIG. 1 is a front elevational view of hand luggage, showing my new design;

FIG. 2 is a left side elevational view;

FIG. 3 is a right side elevational view;

FIG. 4 is a top plan view;

FIG. 5 is a bottom plan view; and

FIG. 6 is a rear elevational view.

The characteristic feature of the design resides in the two 3-ribbed columns shown on the side panels.

FIG. 4

FIG. 2

FIG. 1

FIG. 3

FIG. 5

FIG. 6
